ACTION TOY SAVINGS BANK

Steven Berzack, Hazel Park, and John Berzack,
St. Clair Shores, Mich.

Application May 1, 1957, Serial No. 45,961

Term of patent 14 years

(Cl. D34—11)

Fig. 1 is a side elevational view of an action toy savings bank showing our new design;

Fig. 2 is a front elevational view of the bank shown in Fig. 1;

Fig. 3 is a lower end plan view of the bank shown in Fig. 1; and

Fig. 4 is a perspective view of the bank shown in Fig. 1 to a larger scale.

We claim:

The ornamental design for an action toy savings bank, substantially as shown and described.
